UNITED STATES PATENT OFFICE.

TULLIO GIARA, OF BOSTON, MASSACHUSETTS.

PNEUMATIC TIRE.

SPECIFICATION forming part of Letters Patent No. 784,738, dated March 14, 1905.

Application filed April 19, 1904. Serial No. 203,908.

To all whom it may concern:

Be it known that I, TULLIO GIARA, a subject of the King of Italy, and a resident of Boston, in the county of Suffolk and State of 5 Massachusetts, have invented certain new and useful Improvements in Pneumatic Tires, of which the following is a specification.

My invention relates to improvements in pneumatic tires, and especially to a protective 10 shield which has for its object to prevent the air-chamber from being punctured by nails or like articles which may cut through the outer tube surrounding the inner tube which forms the air-chamber.

15 In carrying out this invention the protective shield is placed inside the tire between the inner and outer tubes.

My invention consists of certain novel features hereinafter described, and particularly 20 pointed out in the claims.

In the accompanying drawings, which illustrate a construction embodying my invention, Figure 1 is a vertical section of a cycle-rim with a tire constructed according to my invention. Fig. 2 is a detail plan view, partly 25 in section, of the improved protective shield. Fig. 3 is a longitudinal sectional view through the protective shield. Fig. 4 is a vertical cross-section on the line X X, Fig. 2, through 30 the protective shield.

Like letters of reference refer to like parts throughout the several views.

On the rim A is located the inner tube C, constituting the air-chamber, and held in 35 place on the rim by the tube B, as shown, or in any other desired manner. Located over the inner tube is a layer D, of prepared cloth, and between said layer of cloth and the outer tube B is located the protective shield, which 40 consists of compressed layers G and H, of cotton, which have been previously subjected to the action of a suitable solution to give them the proper binding property, and, if desired, to the action of an oxid to cause them to retain 45 their flexibility. The layer G is turned in at the edges, as shown in Fig. 2, and its opposite layer H is formed with a series of pockets J in the manner indicated in Fig. 3, and in these 50 pockets are located flexible thin overlapping steel plates K in the form of scales. Against 55 the back of the layer H is a piece of gummed

cloth L. These three layers of cloth are enclosed by sheets of rubber F F' or directly-vulcanized rubber, and all the parts are then fixed together to hold each part in a determined position, so that the parts cannot shift after the shield has been placed in position between the outer and the inner tube. These thin flexible steel plates give elasticity to the tire in contradistinction to rigid sheets of 60 metal, which reduce the elasticity of the tire. As shown, the shield E is thinner at its edges than at the middle and curved in accordance with the inner tube C forming the air-chamber and of such size as to cause a nail or other 65 cutting-surface which may pierce the tire-cover to come into contact with the flexible metal plates and prevent puncture of the air-chamber. It will be understood that the shield being light and flexible will yield to 70 any cutting-surface which pierces the outer tube and compresses the air-chamber it surrounds, the fibers and the thin metal plates preventing the cutting-surface from passing through the inner tube and puncturing the air-chamber. 75

The rubber sheets F F' prevent the entrance of water to the steel plates K, thereby preventing oxidation of said steel plates, which would cause them to break. After a nail or other sharp surface has passed through the outer tube and has come into contact with the shield and has been withdrawn the rubber of the shield closes up and prevents entrance of 80 water to the steel plates. 85

I do not limit myself to the arrangement and construction shown, as the same may be varied without departing from the spirit of my invention.

In practice it may be desirable to cement 90 the protective shield to the inside of the tube, so that when the parts are assembled the shield will remain in its proper position.

Having thus described the nature of my invention and set forth a construction embodying the same, what I claim as new, and desire to secure by Letters Patent of the United States, is— 95

1. A protecting-shield for tires consisting of layers of textile material treated with a binding substance to stick them together and with a flexibility-retaining substance, metal 100

plates inclosed by said layers of textile material, and a rubber covering inclosing said layers of textile material.

2. A protecting-shield for tires consisting of layers of textile material treated with a binding substance to stick them together and with a flexibility-retaining substance, overlapping metal plates inclosed by said layers of textile material, and a rubber covering inclosing said layers of textile material.

3. A protecting-shield for tires consisting of layers of textile material treated with a binding substance to stick them together, overlapping metal plates inclosed by said layers of textile material, and a rubber covering inclosing said layers of textile material.

4. In a protecting-shield for tires consisting of layers of textile material treated with a binding substance to stick them together, overlapping metal plates inclosed by said layers of textile material and inclosed in pockets between said layers, and a rubber covering inclosing said layers of textile material.

In testimony whereof I have signed my name to this specification, in the presence of two subscribing witnesses, this 16th day of April, A. D. 1904.

TULLIO GIARA.
